CLAIM

The ornamental design for a bottle, as shown and described.

DESCRIPTION

FIG. 1 is a top front perspective view of a bottle showing our new the claimed design;

FIG. 2 is a bottom front perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a second top view thereof;

FIG. 10 is a third top view thereof;

FIG. 11 is a fourth top view thereof;

FIG. 12 is a fifth top view thereof;

FIG. 13 is a sixth top view thereof;

FIG. 14 is a seventh top view thereof;

FIG. 15 is an eighth top view thereof;

FIG. 16 is a ninth top view thereof;

FIG. 17 is a tenth top view thereof;

FIG. 18 is an eleventh top view thereof;

FIG. 19 is a twelfth top view thereof;
